UNITED STATES PATENT OFFICE.

EDMOND JONES, OF CLEVELAND, OHIO, ASSIGNOR OF ONE-HALF TO ALFRED ALLEN, OF CLEVELAND, OHIO.

ADJUSTABLE SCAFFOLD.

Application filed January 18, 1923. Serial No. 613,439.

To all whom it may concern:

Be it known that I, EDMOND JONES, a citizen of the United States, and resident of Cleveland, in the county of Cuyahoga and 5 State of Ohio, have invented certain new and useful Improvements in Adjustable Scaffolds, of which I hereby declare the following to be a full, clear, and exact description, such as will enable others skilled in the 10 art to which it appertains to make and use the same.

The objects of the invention are to provide an improved form of vertically adjustable bracket or scaffold for the use of carpenters, painters, bricklayers and other artisans, and it comprises a standard having a ladder at one or both ends and also provided with vertical guides in which brackets supporting a platform upon which the 15 artisan stands are vertically movable, and also includes mechanism by means of which the artisan can raise or lower the platform without leaving the same.

It also includes folding supports for the 20 scaffold, permitting it to be folded in small compass for storage and transportation.

The invention is hereinafter more fully described, illustrated in the accompanying drawings and specifically pointed out in the claims.

30 In the accompanying drawing, Fig. 1 is a perspective of the complete device.

Fig. 2 is a side elevation of the same and Fig. 3 is a front elevation thereof. Fig. 4 is a detail of the brake mechanism.

35 Figure 5 is a detail view of one of the spacing and locking blocks which are utilized at the bottom of the scaffold support.

Referring to the drawings which illustrate 40 one of many possible embodiments of the invention, the reference characters A designate a pair of ladders which are adapted to be supported in an upright position, said ladders having a spaced relation and being arranged in substantially the same vertical 45 plane when they are in use. Arranged at the base of the ladders and extending across the support at the front and rear respectively of the ladders are the horizontal base members or bars 1-1. Extending rearwardly from the ends of the base members 50 1-1 are horizontal supporting strips 2-2 which have the rear ends thereof connected to the top portions of the respective ladders by the diagonal braces 3-3. Similar transverse strips or feet 4-4 are hingedly con-

nected at 5 to one of the base members 1, so that they can either be swung outwardly into operative position, as indicated by Figure 1, or folded against the base member.

Arranged in a spaced and parallel relation to the inner side of each of the ladders A is a vertical guide member or strip 6. These guide strips 6 are provided with racks 7 and are separated from the upper ends of the ladders by spacing blocks 8 and from the lower ends of the ladders by the spacing blocks 9. One of the spacing blocks 9 is shown in detail by Figure 5, and it will be observed that the end portions of the spacing block are adapted to overhang the base members 1 and are notched at 10 to interlock therewith. The middle portion of the spacing block is formed with an opening 11 and these openings receive the bolts 12 which are utilized for securing the transverse base strips and vertical guide strips to the lower ends of the ladders. Similar bolts 13 are utilized at the top of the ladders for attaching the diagonal braces and blocks thereto. The upper ends of the ladders are connected 70 by a transverse top bar 14, said bar having blocks 15 secured thereto and these blocks being engaged by the bolts 13.

The platform 16 of the scaffold is mounted upon and carried by a pair of brackets 17 which are mounted to slide up and down upon the ladders and vertical guide strips 6. The brackets extend through the spaces provided between the ladders and the respective guide strips 6 and are provided with the 80 front and rear guide bars 18 which slidably engage the vertical guide strips 5 and adjacent sides of the respective ladders at the front and rear thereof, so that the brackets are held against tilting. The rear guide bars 18 may extend upwardly above the platform and brackets and be connected by the transverse guard rails 19.

A windlass 20 is provided for raising and lowering the platform and brackets and this 100 windlass is adapted to be operated by a crank shaft 21 through the medium of the gearing 22. A conventional pawl and ratchet 23 is associated with the windlass to prevent backward rotation thereof.

Cables 24 are wound upon the drum of the windlass and extend in opposite directions therefrom. These cables pass around pulleys 25 upon the platform and from these pulleys extend upwardly and around pul-

leys 26 which are arranged at the upper portion of the support, being shown in the present instance as mounted upon the spacing blocks 8. After passing around the upper pulleys 26 the cables are carried downwardly and secured to the platform. With this construction it will be obvious that by operating the windlass to wind up the cables the platform can be raised. When it is desired to lower the platform the pawl and ratchet mechanism 23 is rendered inoperative by disengaging the pawl from the ratchet and the lowering of the platform can be controlled by grasping the crank shaft 21 and controlling the speed of rotation of the windlass drum.

The platform is provided with an automatically acting brake device to prevent accidental falling thereof. This brake device includes the sliding bolt rods 27 which extend loosely through the guides 28 and terminate at their outer ends in noses adapted to engage the teeth of the racks 7. The inner ends of the locking bolts 27 terminate in curved end portions 29 which cross each other, as indicated quite clearly by Figure 4. The crossed ends are connected by a tension spring 30 which normally tends to slide the bolt rods outwardly and hold the outer ends thereof in operative engagement with the racks 7. The crossed inner ends of the guide rods are also connected by the toggle levers 31 which provide a means for moving the locking bolts into inoperative position. When lowering the platform the operator must place one of his feet upon the toggle levers 31 and push the toggle levers downwardly to expand the same and retract the locking bolts 27 into inoperative position. When the locking bolts are thus released and held in inoperative position the platform can be lowered, although at other times the locking bolts will cooperate with the racks to render an accidental dropping of the platform impossible.

Having described the invention what I claim as new and desire to secure by Letters Patent is:

1. In an adjustable scaffold, the combination with a pair of spaced upright ladders, of guide bars spaced from the sides of the respective ladders, brackets slidable between the ladders and the guide bars, a platform carried by the brackets and means for raising and lowering the brackets.

2. An adjustable scaffold, including spaced upright ladders, guide bars spaced from the respective ladders, brackets slidable between the guide bars and the ladders, upright guide strips applied to the brackets and slidably engaging opposite sides of the ladders to prevent tilting of the brackets, a platform upon the brackets, and means for raising the brackets.

3. An adjustable scaffold including spaced vertical ladders, guide bars spaced from the respective ladders, brackets slidable between the guide bars and the ladders, guide means on the brackets slidably engaging the ladders to prevent tilting of the brackets, a platform on the brackets, means for raising the brackets, and locking means upon the platform engaging the guide bars to hold the brackets and platform in an adjusted position.

4. An adjustable scaffold including upright guide members, a platform, means for slidably mounting the platform on the guide members, means for raising the platform, locking bolts mounted upon the platform and adapted to engage the guide members to hold the platform in position, the inner ends of the locking bolts overlapping each other, yielding means normally tending to move the locking bolts into operative position, and toggle levers connecting the overlapping inner ends of the locking bolts for moving the locking bolts against the action of the yielding means to release the same.

5. In a device for the purpose described, vertical ladders spaced apart, guide means on the adjacent sides of said ladders, brackets, slidable in said guides, a platform secured to said brackets, front and rear parallel members between which said ladders are inserted, backing blocks therefor, a top member connecting the tops of said ladders, horizontal base members extending towards the front and rear from said ladders, one of said base members being foldable, and brace members connecting said rearwardly extending base members with the upper ends of said ladders.

In testimony whereof, I hereunto set my hand this 16th day of December, 1922.

EDMOND JONES.

In presence of—
W.M. M. MONROE,
ALFRED ALLEN.
